UNITED STATES PATENT OFFICE.

EMILIO MAGALDI, OF PARIS, FRANCE.

BELTING.

SPECIFICATION forming part of Letters Patent No. 761,519, dated May 31, 1904.

Application filed September 24, 1901. Serial No. 76,381. (No model.)

To all whom it may concern:

Be it known that I, EMILIO MAGALDI, a subject of the King of Italy, and a resident of Paris, France, have invented Improvements in 5 Belting and the Like, of which the following is a full, clear, and exact description.

This invention relates to the manufacture of articles of leather or like material in which great strength is required with flexibility, and 10 the invention is particularly applicable to the manufacture of belting.

In the accompanying drawings, Figure 1 shows a part of a leather strip to be used in making the belt or like article. Fig. 2 shows 15 the same with holes punched in it. Fig. 3 is a face view of part of the finished belt, and Fig. 4 is an edge view of the same.

In carrying out my invention I take a leather strip or thong A, Fig. 1, preferably 20 having as great a length as possible; but that is in no way indispensable, because I may use thongs of any length and portions of cut strips. The thongs are placed together parallel, Fig. 3, and are joined by metal rods or 25 pins B B, passed through openings previously formed in the latter, Fig. 2. The pins B are riveted at b at their ends, so as to strongly compress at those points the whole width of the thongs, Figs. 3 and 4. In general the 30 thongs are placed in such a manner that the faces of the strap or belt are formed by the faces of the thongs resulting from the cutting into the sheet of leather by means of which they have been made. I thus obtain a built-

35 up strap, such as that shown in Fig. 3, which consists of a series of zones α , in which the thongs are relatively free, although bound or pressed together at B. In these last-mentioned parts the leather thongs are very 40 strongly pressed and form at these parts a mass similar to a single broad belt of leather. The further result of this arrangement is that the thongs between two consecutive pins B are slightly bulged out and incurved, particularly 45 in the case of the outer thongs, as clearly seen in Fig. 3. Such a built-up strap or belt is very flexible, because it is to a certain extent similar to a leather belt or chain composed of links, (known as "leather-link" belting,) the

thongs being free and retaining their natural 50 flexibility in the zones α , but having at the same time the qualities of great strength, because the parts about the pins or rods B are solid and comparatively inflexible. The strap or belt is similar as regards flexibility to a 55 solid strap in which longitudinal slits or incisions might have been made, but with much superior qualities, because such a strap would tend to be torn, while mine is composed of parallel elements the breakage of any one of 60 which is without effect upon the others. Again, built-up belts according to this invention when they stretch at the time of starting do not become weakened. An ordinary strap tends, in effect, to become thinner or narrower, 65 and therefore to be less strong at one or more parts, since a strap cut from a sheet of leather is never of equal thickness and quality throughout. When my belt is subject to a 70 tractive strain, it does not diminish in thickness; but by reason of the curve and bulge of the thongs between two successive pins B the distance between the pins increases and returns to its original dimension when the force of 75 traction ceases.

It is to be noted that the strap or belt is not 75 weakened about the rods B, because, as has been stated, the perforations intended to allow the insertion of these rods are not punched out or cut, but are simply opened by means 80 of a pointed punch, so that the pins B are engaged in opening and forcing aside the surrounding leather.

My improvement enables me to utilize the 85 most varied parts of leather, for the thongs work individually only between the rods B, and at the position of these latter they are rendered solid by the very great pressure with which they have been forced or bound against one another. I can thus construct the strap 90 or belt by distributing over its width the weakest thongs. When it is desired to join two thongs, I effect this at the place of a rod, as shown in Fig. 3, by cutting the ends of the thongs in sloping fashion or scarf'd.

I claim as my invention—

As a new article of manufacture, homogeneous belting composed of thongs of leather

placed together longitudinally side by side with rods passing through the thongs at intervals, the material being tightly compressed toward the center from both sides at the points 5 where the rods pass, thereby holding the thongs together in a solid inflexible mass at those points and the parts of the thongs between adjacent rods being symmetrically curved outwardly on both sides from the cen-

ter and free from pressure and retaining there 10 the natural flexibility of the material.

In testimony whereof I have signed my name to this specification in the presence of two subscribing witnesses.

EMILIO MAGALDI.
